236,447

COMBINED BOAT AND PICKUP TRUCK BODY COVER

Robert R. Roloff, Sr., 1155 Morningside Drive,
Hubbard, Ohio 44425

Filed July 24, 1972, Ser. No. 274,833

Term of patent 14 years

Int. Cl. D12—06, 16

U.S. Cl. D12—62

FIG. 1

FIG. 2

FIG. 3

FIG. 4

FIG. 5

FIG. 1 is a top plan view of the combined boat and pickup truck body cover showing my new design;

FIG. 2 is a side elevational view thereof;

FIG. 3 is a front elevational view thereof;

FIG. 4 is a rear elevational view thereof; and

FIG. 5 is a perspective view thereof.

The side opposite to that shown in FIG. 2 is a mirror image thereof.

I claim:

The ornamental design for a combined boat and pickup truck body cover, as shown and described.
